Charles Holland
ATTORNEY

UNITED STATES PATENT OFFICE

WALTER S. JOSEPHSON, OF BROOKLYN, NEW YORK, ASSIGNEE TO DRYICE CORPORATION OF AMERICA, OF NEW YORK, N. Y., A CORPORATION OF DELAWARE

CONTAINER FOR REFRIGERANT

Application filed December 31, 1929. Serial No. 417,637.

This invention relates to refrigerating packages or containers, and is especially adapted for use with a refrigerant such as hydrated solid carbon dioxide as described and claimed in my copending application Serial No. 399,911.

The invention also relates to a method of refrigerating which, while adaptable to any kind of refrigerant, is most advantageously employed with the hydrated solid carbon dioxide of my aforesaid copending application.

The container comprises a housing or shell having a reentrant portion, which I consider a separate element thereof, although it may be, and ordinarily is integral with the housing. The material to be refrigerated may be packed into the container in contact with the reentrant element which is preferably made of a good heat conducting material although the housing or shell may be, and for best results should be of poor heat conducting material. The reentrant element is adapted, both as to material of which it is composed and as to the form in which it is constructed to receive a solid refrigerant. I have already pointed out in my said copending application for patent upon hydrated solid carbon dioxide and upon various devices for employing this refrigerant, that a large portion of the moisture content of the refrigerant will, on melting of the refrigerant block, build up on the surface of the block as a blanket of water snow of a thickness dependent upon the volume of the block and upon its moisture content. The blanket, so deposited, is of a temperature of ordinary water snow or ice on its outer limit, namely, 32° F.

It acts, however, as a thermostatic control preventing the rapid melting of the block or stick, for although it has a temperature of 32° F. on its outer limit, the blanket temperature rapidly descends upon its inner margin where it contacts with the block, to approximately the temperature of the block, or about -109° F.

The present invention contemplates a shell preferably of cardboard or other material of poor heat conducting properties and which

may be of cylindrical conformation and a reentrant element of preferably tubular form closed off from the interior space of the shell. The side of the shell with which the reentrant element connects may be either of the same material as the shell or of another material having better heat conducting properties. It may be of the same material as the reentrant element which should have good heat conducting properties and for this, commercial sheet tin is satisfactory.

The invention will be clearly understood from the drawing in which Fig. I shows, in sectional elevation, a container of the present invention adapted to ice cream and Fig. II shows a plan view thereof.

Referring to Fig. I, 1 represents a shell preferably of cardboard having an interior space, 2, which is the space to be refrigerated, surrounding the reentrant element or refrigerant receptacle, 3, the said reentrant element, being composed preferably of tin sheet and integral with the bottom of said shell with which it unites at 4. The reentrant element protrudes up through the center of the container and is shown concentric therewith. A stopper, 5, of cork or other material having perforations, 6, closes the refrigerant receptacle, but allows the escape of gas from the melting block through the perforations.

When the material to be refrigerated, such as ice cream is closely packed into the space, 2, surrounding and in contact with the reentrant element or refrigerant receptacle, 3, which is out of communication with space, 2, a stick or block of refrigerant such as hydrated solid carbon dioxide is inserted into the receptacle, 3, and closed by means of the cork or stopper, 5. A covering, 7, is then placed over the top of the container and another cover, 8, having an opening or openings, the openings therein corresponding to the openings, 6, through the cork, 5, but not necessarily registering therewith is placed in position over the bottom of the container.

Fig. II showing the bottom of the container proper illustrates the preferred cylindrical form of the package. The bottom of

the shell, or container, 1, has a central opening through which the reentrant element or refrigerant receptacle, 3, penetrates. This receptacle which is made of tin or other 5 similar heat conducting material joins with the bottom at, 4.

The function of the device is obvious from the drawing and the description above given in connection therewith.

- 10 The refrigerant, hydrated solid carbon dioxide, may be made at some place other than the place where the container is to be packed, and is compressed in a hard solid stick or block and in that form inserted 15 into the reentrant element or refrigerant receptacle, 3. As the refrigerant melts and gives off hydrated carbon dioxide in gaseous form a very considerable pressure would take place within the reentrant element or 20 refrigerant receptacle due to the enormous expansion of the hydrated gas coming off from the block, were it not for the fact that the openings, 6, through the stopper, 5, and through the bottom cover, 8, permit 25 the gas expanding from the melting solid to escape.

The invention comprises a method as well as the specific device hereinabove disclosed. In my said copending application Serial 30 No. 399,911, I have described and claimed a refrigerating material, hydrated solid carbon dioxide. This material consists of carbon dioxide and moisture, which have been solidly compacted and in which the 35 moisture content has been predetermined. As the solid melts the moisture content is given off in gaseous form with gaseous carbon dioxide but a considerable portion thereof immediately condenses upon the surface 40 of the solid in a water snow blanket the thickness of which depends upon the volume of the solid and the percentage of moisture therein.

The thickness of the water snow blanket, 45 therefore, can be predetermined by predetermining the factors on which it depends. I have found that when this blanket is from one half inch to one and a half inch thick, it has a temperature on the outside of 32° F. 50 and that its temperature descends sharply toward the block until it is approximately -109° F. where it contacts with block. The temperature of the outside may be increased or diminished in accordance with the 55 greater or less thickness of the water snow blanket. Moreover, the pores of the water snow are filled with carbon dioxide gas given off from the block. The effect of the water snow blanket thus permeated with the 60 carbon dioxide gas, which is a very poor heat conductor, is that of a natural thermostatic control.

The valuable refrigerating function of this 65 will be readily seen from a comparison of my hydrated solid carbon dioxide with or-

dinary pure dry solid carbon dioxide. The latter as a refrigerant is capable of imparting a most intense cold or about -109° F. to the space to be refrigerated. It is obvious therefore, that if we assume that the container 70 of the present invention were to be filled with ice cream and the reentrant receptacle were to receive a block or stick of dry solid carbon dioxide, such a low temperature would be imparted through the conductive 75 walls of the receptacle that the ice cream in the container would be frozen so hard that it could be cut only by the most forceful methods.

On the other hand, if instead of dry solid 80 carbon dioxide, the hydrated solid carbon dioxide of my said copending application were placed in the reentrant receptacle, the thickness of the water snow blanket can be predetermined by predetermining the percentage 85 of moisture in the block or stick. It is thus possible to obtain any desired predetermined temperature to keep the materials to be refrigerated in the most desirable condition for use. 90

In the reentrant receptacle of the container, a refrigerant may be placed as desired which contains either a preponderance of carbon dioxide or a preponderance of moisture. Indeed, pure dry carbon dioxide solid 95 may be employed and so may ordinary water ice, if the conditions of time of refrigeration and degree of temperature during that time require one or the other. It is assumed, however, that the container will be 100 particularly serviceable and find its most valuable uses with the hydrated solid carbon dioxide of my said copending application.

The container of the present invention may 105 obviously be made in any size or shape to contain any materials it is desired to transport either by hand or otherwise and which must be refrigerated during transport. It is also obvious that the reentrant receptacle 110 may be of any shape or relative size relative to the shape or size of the shell of the container. Many other modifications of the device may also be made without departing from the scope of the invention all of which I desire to claim. 115

What I claim is:—

1. A method of refrigerating at moderate relatively high, relatively constant temperatures, which method includes absorbing heat through the walls of a container and applying it to effect phase changing action of low melting point solid carbon dioxide intimately associated with relatively high temperature phase changing moisture, thereby depositing an insulating, moderate-temperature 120 blanket of frozen moisture on the solid as it passes from its interior, variably heating the exterior surface of said container by enclosing a product to be refrigerated in contact with said surface, thereby removing 125

moisture from the surface of said blanket at rates varying automatically with variations in heat applied by the product.

2. A method of refrigerating at moderate 5 relatively high, relatively constant temperatures, which method includes absorbing heat through the walls of a container and applying it to effect phase changing action of low melting point solid carbon dioxide intimately 10 associated with relatively high temperature phase changing moisture, thereby depositing an insulating, moderate-tempera-

ture blanket of frozen moisture on the solid as it passes from its interior, variably heating the exterior surface of said container by enclosing a product to be refrigerated in contact with said surface, thereby removing 70 moisture from the surface of said blanket at rates varying automatically with variations in heat applied by the product; and draining all excess gas or moisture downward and discharging it into the exterior atmosphere. 75
